UNITED STATES PATENT OFFICE

EMIL A. ZETTMER, OF TOPEKA, KANSAS

WINDOW CONSTRUCTION

Application filed September 18, 1931. Serial No. 563,520.

My invention relates to means whereby sliding windows may be made weather-proof and at the same time permitting the windows to be easily operated; and although I have illustrated the invention in connection with a double type of car window, it will be understood that the invention is equally applicable to other types of windows.

For purposes of exemplification, the invention has been shown applied to a railroad passenger car window to which it is especially applicable and whereby certain parts at present involved in passenger car windows are eliminated, while at the same time a better weather sealing or stripping of the usual double windows of a car is obtained.

My invention also involves an improved window guide and window-locking and holding means for maintaining the window in locked or in the desired raised position, while at the same time providing easy manipulation of the windows.

The objects and advantages of my invention will be readily comprehended from the following detailed description of the accompanying drawings wherein:

Figure 1 is an elevation of a car window as viewed from the car interior, with an intermediate portion broken away.

Figure 2 is an enlarged cross-sectional view taken substantially on the line 2-2 of Figure 1.

Figure 3 is an enlarged vertical sectional view taken substantially on the line 3-3 of Figure 1, as viewed by the arrows.

Figure 4 is an enlarged perspective view of a portion of a side of the outside window.

Figure 5 is a perspective view of a portion of the window frame, weather striping, outside window guide and locking rack.

My improved window construction is especially intended for railroad passenger cars and in the specific embodiment it is shown in connection with the double,—namely the inside and outside—windows of a passenger car.

In Figure 1 a portion of the interior car wall and a window casing is shown; a por-

tion of the window casing being more clearly shown at 10 in Figure 2, provided with a metallic finish panel 11 on the car interior; while the outer wall is provided with the stop rail or member 12.

The window casing on the inner side is shown provided with a curtain slide rail 13.

Slidably mounted intermediate of the stop rail 12 and the curtain slide 13 are the outside window 14 and the inside window 15.

Secured to the opposite sides of the window casing or opening and adjacent to the stop rail 12 is a vertically disposed slide-forming channel member 16, preferably made of metal, with the channel of sufficient depth and width to receive the side sash members 17 of the outside window 14 and constitute a slideway for the sash; the channel member 16 being suitably secured in place as for example by the screws 18; it being understood that the channel members 16 extend throughout the height of the window opening.

The channel members 16 on each side of the window opening are identical, with the outer leg or side of each channel member 16 of greater width and bent into the inwardly disposed groove forming portion 19. This groove forming portion is provided with a weather strip 20 of suitable yieldable material, such as rubber or felt, which is clamped in place in the groove forming portion 19.

The channel member 16, at each side of the window opening at an intermediate point in the channel, is formed to provide a vertically extending rack forming rib 21 which is provided with vertically spaced apart shoulders 22, while the rib intermediate of the respective shoulders 22 is made to slope inwardly toward the next subjacent shoulder as at 23 in Figure 5. Adjacent to the lower end, the rib 21 is provided with a notch or slot 24, thus providing the two locking shoulders or stops 25, 26, adapted to receive the end of the locking rod 27 therebetween when the window is in full closed position, see Figure 1.

The side sash members 17 of the outer window are shown provided with the sash

protector 28, preferably of sheet metal and of channel formation to fit snugly about the sash sides as shown in Figure 2. The protector 28 is bent to provide a rib 29 which is embedded in the side sash member 17 and is adapted to receive the rack forming rib 21 of the slideway channel 16. The protector member 28 is securely fastened to the outer sash 14 in any suitable manner as by 5 the screws 30. The side of the protector member 28, disposed toward the car exterior, is of greater width so as to extend slightly beyond the weather strip 20; and the outer vertical edge of this side is preferably flanged outwardly as at 31 to lap the side of the weather strip 20 as shown in Figure 2; and the protector 28 is preferably made wider at the bottom to permit it to lap the bottom sash rail 32 and also be secured thereto as shown in Figure 4.

The bottom member 32 of the outer sash 14 is shown provided with finger grasping members 33, 33 which control the locking or latch rod 27 and retract the rod 27 from engagement with the rack rib 21 when the members 33, 33 are pressed together.

The window sill, shown at 34, is provided with a shoulder at 35 disposed on the inner side of the outer window. The bottom member 32 of the outer window 14 is dished or concaved throughout as shown in Figure 3, to receive a suitable weather strip 36 of suitable flexible material; the strip 36 being preferably of slightly greater width than 35 the thickness of the sash.

The strip 36 is held in place by a suitable strip 37, preferably of metal, and the strip 37 held in place by screws 38 which extend through the weather strip 36 and into the 40 bottom member 32 of the sash.

By dishing the sash as shown, the outer free longitudinal edge of the weather strip 36 is bent downwardly into snug relation with the window-sill 34; while the inner longitudinal edge of the weather strip 36 is in contact with the shoulder 35 of the window-sill, thus completely sealing the contact between the bottom of the outer sash 14 and the window-sill.

50 In order to provide an air-tight condition at the top of the outer sash, I provide the top rail or member 39 of the outer sash 14 with a weather strip 40 extending longitudinally of the sash preferably secured in place 55 by an angle plate 41 which is secured to the window-sash by screws as at 42.

Secured to the car wall within the sash receiving space above the window opening is a metal trough member 43 suitably secured 60 in place as for example by screws as at 44. In order to properly position the lower trough portion and to position the lower longitudinal edge of the weather-strip 40 so it will enter or seat in the trough, I provide 65 a wedge shape block 45 to the rear of trough

member 43 held in place on the car wall by the screws 44; and also provide a wedge shape block 46, secured to the sash by the screws 42, rearward of the weather-strip. It is apparent that the lower free longitudinal edge of the trough will receive the lower longitudinal edge of the weather-strip when the window 14 is closed and an air-tight relation provided.

The vertical side members 47 of the inner sash 15 are each provided with a metallic protecting channel plate 48, whose sides lap the sides of the sash member 47 and are secured thereto by screws as shown in Figure 2. The plate is also formed with the vertically disposed arcuate portion 49, countersunk in the sash member 47. This arcuate portion 49 provides a groove to receive the rack forming rib and sash guide 50 shown formed integral with the slideway forming channel member 51 which is suitably secured to opposite sides of the window casing and extending from top to bottom.

The rack forming rib and sash guide 50 is similar in construction to the rib 21 described in connection with the outer sash and shown in Figure 5; and the lower rail of the inner sash is also shown provided with similar finger grasps and control members 33, see Figures 1 and 3, which control the laterally movable latch rods 27 and retract them from engagement with the stop shoulders of the rack.

It is apparent from the construction shown and described that comparatively free sliding sashes are provided by the metal to metal contacts at the sides of the sash, while at the same time a comparatively simple weather sealing construction is provided, whereby an air-tight condition at the sides, top and bottom of the outer sash is obtained and an effective air sealing condition with the sides of the inner sash is also provided, while at the same time providing means which will permit the windows to be raised readily and will not be affected by moisture.

As my invention is especially applicable to railroad passenger car windows, it has been so shown and described, but it is apparent that the invention is applicable to any sliding type of window.

I have shown what is believed to be a simple embodiment of the invention, which has been described in terms employed merely as terms of description and not as terms of limitation, as modifications may be made without, however, departing from the spirit of my invention.

What I claim is:

1. In a window construction, channeled members secured to opposite sides of the window opening and slidably receiving the sides of a window-sash, the members being provided with rack forming ribs, intermediate of the sides of the members, with one

- side of each member provided with a weather-strip disposed toward the side rail of the sash.
2. In a window construction, a vertically disposed channel member secured to each side of the window opening and slidingly receiving the sides of a window-sash, each member being provided with a rack forming rib intermediate of the sides, while the outer sides of said members are provided with weather sealing means disposed toward the outer faces of the side rails of the sash; and channel members secured to the side rails of the sash and adapted to seat in the first mentioned channel members, said last mentioned channel members having a groove portion countersunk in the sash side rails and adapted to receive said rack forming ribs. 70
3. In a window construction, a vertically disposed channel member secured to each side of the window opening to provide a sash slideway, each member having one side extended and formed to hold a weather sealing element disposed toward the face of the sash side rail, a channel member secured about the sash side rails and slidable in the first mentioned channel members and formed to contact with the weather sealing element; and means for locking and holding the sash in closed and raised positions. 80
4. In a window construction for a sliding sash, channel members secured to opposite sides of the window opening and adapted to slidingly receive the side rails of the window sashes, said members on the base of the channels being provided with rack forming ribs adapted to extend into grooves in the side rails of the window-sashes. 85
5. In a window construction for a sliding sash, metallic channel members secured to the side rails of the window-sashes with the sides of the members lapping the side faces of the sash side rails, said members having groove forming portions countersunk in the sash side rails; and channel members secured to both sides of the window openings with the sides of the members lapping the sides of the first mentioned members and provided intermediate of the sides with rack forming ribs extending into the groove forming portions of the first mentioned members. 90
6. A window construction comprising, in combination with slidably mounted window-sashes whose side-rails are grooved vertically, channel members secured to the sides of the window-openings with the sides of the members lapping the faces of the sash side-rails and provided intermediate of the sides with ribs disposed into the grooves in the sash side rails, one side of each member being formed to provide a socket disposed toward the window-sash; and weather sealing means secured in said sockets and disposed toward the side rails of the sashes. 95
7. In a window construction, vertically slidable window-sashes whose side rails are provided with vertical grooves, channel members secured to opposite sides of the window openings, adapted to slidily receive the sashes, said members being provided with vertically disposed rack forming portions adapted to extend into the grooves of the sashes, the outer sides of the channel members being provided with weather sealing means disposed toward the outer faces of the sash side rails. 100
8. A window construction, comprising the combination of vertically slidable window-sashes, channeled metallic members secured to the side rails of the sashes with groove forming portions, with channeled means secured to opposite sides of the window openings and provided with rack forming ribs extending into said groove forming portions, and latch members mounted in the bottom rails of the sashes and adapted to engage with said rack forming ribs. 105
9. A window construction comprising the combination of vertically slidable window-sashes, channeled members secured to the side rails of the sashes and having groove forming portions countersunk in the side rails; with channeled means secured to opposite sides of the window openings adapted to slidily receive the side rails with the channeled members, said means being formed to provide rack forming ribs seatable in the groove forming portions of the members, said means on the window outer side being formed with a weather sealing strip holding groove disposed toward the outer face of the sash side rails; and latch members mounted in the sash bottom rails, adapted to engage with the rack forming ribs. 110
10. In a window construction, sash receiving members secured at opposite sides of the window opening, said members on the outer sides being extended laterally to lap the outer sides of the window-sash, with the outer longitudinal margin of said extended portion formed to provide a groove disposed toward the window-sash; and a weather-strip secured in said groove so as to contact with the window-sash. 115
11. In a window construction, plates secured to the side rails of the window-sash and having an outwardly disposed flange; sash receiving members secured at opposite sides of the window opening, said members being formed to lap the plates, with the outer sides of said members formed to provide a groove disposed toward the window-sash; and a weather-strip secured in said groove so as to contact with the plates on the window side rails and with said flanges. 120
12. In a window construction, plates secured to the side rails of the window-sash and having an outwardly disposed flange; sash receiving members secured at opposite sides of the window opening, said members being formed to lap the plates, with the outer sides of said members formed to provide a groove disposed toward the window-sash; and a weather-strip secured in said groove so as to contact with the plates on the window side rails and with said flanges. 125
